UNITED STATES PATENT OFFICE

2,601,457

GUN ADAPTER

David M. Richey, Devon, Conn., assignor to United Aircraft Corporation, East Hartford, Conn., a corporation of Delaware

Application November 22, 1944, Serial No. 564,619

2 Claims. (Cl. 89—37.5)

1

The present invention relates generally to mounts for machine guns, and the like, and more particularly to a novel gun mount having readily releasable means for securing the muzzle end of a gun to a fixed support.

A gun mount made in accordance with the invention comprises a sleeve secured to the forward end of the gun barrel jacket in lieu of the conventional muzzle bearing. This sleeve serves the dual function of providing a bearing for the gun barrel, in which capacity it is a substitute for the conventional bearing, and anchoring the muzzle end of the gun.

One of the objects of the invention is to provide a gun mounting whereby the forces of recoil and counter-recoil will be confined, at least to a substantial degree, at the muzzle portion of the gun.

Another object of the invention is to provide mounting means whereby the element of time required for interchanging of guns is reduced to a minimum.

A further object of the invention is to provide a muzzle mounting means adaptable for use with present gun designs.

A still further object of the invention is the provision of a mounting means for machine guns by which the recoil and counter-recoil loads are taken into a mount which is concentric with the bore, thereby eliminating the eccentric loading generally attendant conventional gun mounting means.

These and other objects and advantages will appear in the following specification, reference being had to the accompanying drawings in which:

Fig. 1 is a side elevation of a machine gun employing one form of the gun mounting means;

Fig. 2 is a perspective view of the mount disengaged from the gun;

Fig. 3 is a longitudinal sectional view showing the mount installation;

Fig. 4 is a transverse view taken along the line 4—4 of Fig. 3;

Fig. 5 is an elevational view of the rear end portion of the gun, showing the rear support, and

Fig. 6 is a perspective view of a bracket employed in the mounting of the rear end portion of the gun.

The invention is herein described as used in conjunction with an airplane, but it is to be understood that it may with equal facility be used on other types of craft and even on ground installations.

2

Reference will now be made to the drawings in which like numerals designate identical parts throughout the various views.

Particular reference will first be made to Figs. 1, 2, 3 and 4 which illustrate in detail a gun muzzle mount comprising two parts in all. Numeral 10 indicates generally the main body of the mount, said body being a sleeve of generally cylindrical form. Intermediate the ends of body 10 is a diametrically increasing mid-portion 11 merging with an external flange 12 at the forward or larger end of mid-portion 11, while near the rear end of the body 10, the mid-portion 11 merges with an external flange 13. Cylindrical portions 14 and 15 adjacent the flanges 12 and 13 have, externally thereof, thread courses 17 and 18 respectively, the purpose of which will be described. The cylindrical portion 15 is provided with an internally thickened portion 19 having an axial bore 20 terminating in a flared portion 21.

A retaining ring 22, internally threaded at 23 and having a flange 24 forwardly thereof, is screwed on the course 17 of sleeve 10.

In attaching this type of mount to a gun, the mount 10 is directed toward the muzzle of a gun barrel 25, the flared portion 21 centering and guiding the barrel 25 into sliding engagement with the axial bore 20. The threads 18 of the cylindrical portion 15 engage internal threads of the gun barrel jacket 26, and are screwed therein until the flange 13 on sleeve 10 abuts the forward end of the barrel jacket 26. Thus, the muzzle mount becomes a unitary part of the gun but does not prohibit recoil and counter-recoil movements of the gun barrel.

It should be noted that a gun employing the new mount has all of the recoiling mechanism, including the gun barrel, cradled in a frame or receiver.

The receiver and the barrel jacket 26 comprise a unitary structure to which the described mount is attached.

Therefore, the reciprocating movement of the gun recoiling mechanism is free to take place, the forward end portion of the gun barrel riding in the bearing comprising the portion 19, and the bore 20.

Referring now to Figs. 1, 5 and 6, the numeral 27 designates a support member which is attached to the airplane structure, preferably in an adjustable manner. Slots 28 in support 27 are adapted to receive for sliding movement the lips 30 of brackets 29, the brackets being rigidly attached to the gun receiver by bolts 31.

The supporting airplane structure, such as may be seen at 38, contains a spherical hole which in turn contains a mounting collar 32 which has a spherically shaped external surface, so as to provide for universal manipulation of the gun, and has a bore 33 and a counterbore 34.

In mounting the gun in an airplane, the lips 30 are first inserted in slots 28 of the support member 27. The mount is then directed into the counterbore 34, until the flange 12 abuts the shoulder 35. The cylindrical portion 14 of the mount will then extend into the bore 33. Retaining ring 22 is then screwed on the threads 17 of cylindrical portion 14 and tightened against the adjacent face of collar 32 so as to draw the flange 12 against shoulder 35. Thus, the sleeve 10 is securely locked to the collar 32 at one end and to the gun jacket 26 at the other end.

The gun may be readily dismounted by simply unscrewing the ring 22 and drawing the gun rearwardly from the collar 32. If desired, the gun barrel of a different caliber gun may be inserted through a suitable adapter (not shown) screwed into threads 36 in the collar opening 33.

It will be observed that the new mount has relatively few parts, is of simple construction, and allows quick and easy installation and dismounting of the gun. The mounting sleeve 10 at the muzzle end of the gun serves to transmit the forces of recoil and counter-recoil through the collar 32 to the structure 38 from the jacket 26, which, of course, is connected to the gun housing or receiver 37. Also, by reason of the rigid support provided by the sleeve 10 at the muzzle end of the gun, the high torsional stresses normally present in firing such guns are greatly reduced. The mounting sleeve 10 serves the dual function of rigidly supporting the muzzle end of the gun jacket 26 and supporting the muzzle end of the gun barrel 25 for sliding movement in the jacket 40 during recoil and counter-recoil.

I claim:

1. A gun adapter for use in combination with a gun having a stationary outer jacket, a recoilable barrel in the jacket, and a fixed support having a partly spherical opening, said gun adapter comprising a partly spherical collar universally mounted in the said opening, a sleeve secured to the jacket having a bearing in which the gun barrel is slidable in recoil, an enlarged external annular portion intermediate the length of the sleeve, a counterbored opening extending through said collar and providing a counterbore shoulder therewithin, said sleeve extending into said counterbore opening and having its said enlarged annular portion in abutting relation with

said counterbore shoulder, and means for locking said sleeve to said collar comprising an internally threaded locking ring arranged to extend into the small bore of said collar in threaded engagement with a threaded portion on said sleeve, and an outwardly extending flange on said locking ring thereby held in abutting relation to a wall of said collar oppositely disposed to said counterbore shoulder.

2. A gun adapter for use in combination with a gun having a stationary outer jacket, a recoilable barrel in the jacket, and a fixed support having a partly spherical opening, said gun adapter comprising a partly spherical collar universally mounted in the said opening, a sleeve secured to the jacket having a bearing in which the gun barrel is slidable in recoil, an enlarged external annular portion having a radially extending surface intermediate the length of the sleeve, a counterbored opening extending through said collar and providing a radially extending counterbore shoulder therewithin, said sleeve extending into said counterbore opening and having its said radially extending surface in abutting relation with said radially extending counterbore shoulder, and means for locking said sleeve to said collar comprising an internally threaded locking ring arranged to extend into the small bore of said collar in threaded engagement with a threaded portion on said sleeve, and an outwardly extending flange on said locking ring thereby held in abutting relation to a wall of said collar oppositely disposed to said counterbore shoulder.

DAVID M. RICHEY.
